INVENTOR
Mervin Wideman
BY
Harry J. Pogorsky
ATTORNEY

one side of the enlargement 14 to the other side, the curl-forming member 4 is forked or split as at 20, or in other words, is provided with a continuous, elongated slot which is constantly located 5 in registration with the hair pin guide-groove 17 provided in the enlargement 11. Thus, when the pin is manually slid through the guide-groove 17 from one end of the same to its other end, it also passes through the slot 20 as will be clear from 10 Fig. 6.

Briefly, the operation of the hair curling device is substantially as follows:

The hair to be curled is first moistened in the conventional manner and then a strand to be 15 formed into a curl is engaged by the comb 2 and combed outwardly from the head thereby. The end of the strand so prepared is next engaged between the finger 12 and the surface of the curl-forming member 4. To prevent slippage of 20 the end of the curl from between the curl-forming member and the finger 12, the curl-forming member may be provided with an elongated depression 21 while the finger may be similarly grooved as shown at 22, or the two meeting surfaces of the 25 parts 12 and 4 may be otherwise roughened or irregularly formed to frictionally engage the hair. With the end of the strand of hair so engaged between the parts 4 and 12, the curl-forming member 4 is then rotated toward the head 30 to wrap or wind up the strand of hair upon it. When the curl-forming member, with the curl wrapped about it, reaches the head, it is turned inwardly to present the end or tip 23 of said member against the scalp and it is lightly pressed 35 against the head to cause it to be pushed out of the curl 15 and to recede within the tube 1 against the tension of the spring 5. The enlargement or abutment 14 is provided with a cut-out section 24 through which the finger 12 may 40 move while it and the curl-forming member are moved out of the curl 15, leaving the curl held flatwise against the head or scalp 16 by the enlargement or abutment 14. At this point a hair pin 16, in the form substantially shown in Fig. 45 8, is inserted in one of the flared ends 18 of the guide groove 17 and forced through said groove by the fingers. The hair pin so moved will embrace the curl and as soon as the hair pin has been fully inserted, as shown in Fig. 6, the curler 50 may be moved away from the head, leaving the formed curl maintained in place flatwise against the head by the hair pin 16.

The hair pin 16 shown in Fig. 8 is preferably provided with the outwardly flared ends 25 to 55 facilitate its passage over the curl when it is inserted through the guide groove 17.

By the device shown, curls may be speedily formed, since it is merely necessary to draw a strand of hair outwardly from the head by the 60 comb 2; engage it between members 4 and 12; rotate the curler to form the curl; place the end 23 of the curler against the head and push lightly to force the member 4 inside of the sleeve 1 and out of the curl and insert a hair pin through the 65 guide groove 17 to embrace the curl, and then move the curler away from the head.

In the modification shown in Fig. 7 the enlargement or abutment 14 is provided with two hair pin guide grooves 27 and 28, the same being 70 substantially similar in construction to that shown in Fig. 4 except that two are provided at an angle to one another so that either two hair pins may be inserted or if only one is used, at least one of the grooves will be presented at a 75 convenient angle to permit it to be easily reached

and the hair pin inserted through it. With this arrangement, the curl-forming member is composed of four segments 29 movable out of suitably shaped segmental openings 30 in the enlargement 14. This and other modifications may 5 be made in the structure without departing from the spirit of the invention.

What I claim is:

1. A hair curling device comprising a guide member, curl-forming means carried thereby and movable relatively thereto, an abutment on the guide member for holding a formed curl against the scalp while the curl-forming means is withdrawn from said curl, and a hair pin guide extending transversely of the longitudinal axis of 15 said member and through which a hair pin may be manually inserted for guiding said pin to cause it to embrace the curl transversely of said curl to hold the curl flatwise against the head when the curl-forming means is withdrawn from 20 the curl, said hair pin guide being located on the abutment.

2. A hair curling device comprising a guide member, curl-forming means carried thereby and movable relatively thereto, an abutment on the 25 guide member for holding a formed curl against the scalp while the curl-forming means is withdrawn from said curl, and a hair pin guide for guiding a pin to cause it to embrace the curl transversely of said curl to hold the curl flat- 30 wisely against the head when the curl-forming means is withdrawn from the curl, said hair pin guide comprising a passage extending across the abutment and passing through the curl-forming means.

3. A hair curling device comprising, a sleeve, a tubular curl-forming member telescopically mounted in the sleeve, a spring within the sleeve operative to force the curl-forming member partly out of the sleeve, an abutment on the sleeve 40 for holding a formed curl against the head while the curl-forming member is forced out of the curl by pressure of said member against the head, a hair pin guide extending transversely of the longitudinal axis of said sleeve provided on the 45 abutment through which a hair pin may be manually forced to cause it to embrace the curl transversely while said curl is held against the head by the abutment.

4. A hair curling device comprising, a sleeve, 50 a tubular curl-forming member telescopically mounted in the sleeve, a spring within the sleeve operative against the curl-forming member to force the same partly out of the sleeve, an abutment on one end of the sleeve for holding a 55 formed curl against the head while the curl-forming member is forced out of the curl by manual pressure of the curl-forming member against the head and against the tension of the spring, a hair pin guide extending transversely of said 60 abutment and facing the formed curl and through which a hair pin may be manually directed to cause the hair pin to embrace the curl transversely of the axis of the curl while said curl is held flatwise against the head by the abutment, and to thereafter hold the curl in position flatwise against the head when the curling 65 device is removed from the curl.

5. A hair curling device comprising, a sleeve having a comb on one end for preparing a strand 70 of hair to be curled, a curl-forming member mounted within the sleeve and extensible out of its other end to engage the strand of hair and enable it to be formed into a curl, a disk-like abutment at the end of the sleeve from which the 75

- curl-forming member emerges for holding the curl so formed flatwisely against the head while the curl-forming member is pushed out of the formed curl and into the sleeve, and a guide 5 through which a hair pin may be manually pushed to embrace the formed curl transversely of the axis of said curl, said guide consisting of a groove extending transversely of the disk-like abutment.
- 10 6. A hair curling device comprising a sleeve, a comb secured on one end of the sleeve for preparing a strand of hair to be curled, a tubular curl-forming member slidably mounted within the sleeve and adapted to partly emerge from the 15 opposite end of the sleeve, a coil spring within the sleeve for engagement with the curl-forming member to force the same partly out of the sleeve, stop-means for limiting the movement of the curl-forming member out of the sleeve, 20 means carried by the curl-forming member for holding the strand of hair against the curl-forming member to permit said strand to be wrapped around said member, an abutment at one end of the sleeve for holding the formed 25 curl flatwisely against the head while the curl-forming member is forced out of the curl and into the sleeve by pressure of one end of the curl-forming member against the head, and guide means for enabling a hair pin to be manually 30 directed to embrace the formed curl transversely of the axis of said curl while it is held against the head by the abutment, said guide means including a groove in the abutment extending transversely thereof and a slot in the curl-forming member through which the hair pin may be 35 passed.
7. In a hair curling device, means for preparing a strand of hair for formation into a curl, a curl-forming element around which the strand 40 is wrapped to form it into a curl, means for holding the curl so formed flatwisely against the head while the curl-forming element is withdrawn from within the curl, and a transverse guide for the reception of a hair pin manually 45 inserted transversely of the curl to embrace and retain the curl flatwisely against the head as the curl-forming element is withdrawn from its position within the curl.
8. In a hair curling device, a curl-forming ele- 50 ment around which a strand of hair is wrapped to form it into a curl, means for engaging the curled strand and holding it flatwisely against the head while the curl-forming element is withdrawn from within the curl, and a guide means 55 for directing a hair pin around and transversely across the curl while the curl is held against the head by the holding means.
9. A hair curling device comprising, a sleeve 60 having a comb at one end and an enlargement at the other end, a tube slidably in said sleeve, a spring in the sleeve operative to normally force the tube partly out of the sleeve, means on the tube for engaging a strand of hair whereby the strand may be wrapped around the tube to form 65 it into a curl, and a guide formed transversely of the enlargement through which a hair pin may be thrust to enable said pin to embrace the curl transversely of the axis of said curl while said curl is held flatwisely against the head by the enlargement.
10. In a hair curling device, a pair of telescopic elements, one of which comprises a member 5 around which a strand of hair is wrapped to form it into a curl, the other member having an element for holding the formed curl flatwisely against the head while the member around which the curl is wrapped is forced out of the curl by 10 pressure against the head, and means on one of said members for guiding a manually moved hair pin transversely of the flatwisely-held curl to cause the hair pin to embrace the curl transversely of the axis of the said curl and hold it 15 flatwisely against the head.
11. A hair curling device comprising, a body portion having a comb at one end and a curling device at the other end, said curling device including a member around which a curl is 20 formed and also including a member for holding the formed curl flatwisely against the head while the forming member is drawn out of the curl, said curling device also including a hair pin guide extending transversely thereof and 25 through which a hair pin may be manually forced to cause the pin to embrace the formed curl transversely of the axis of said curl while the curl is held flatwisely against the head.
12. A hair curling device comprising, a sleeve, 30 a curl-forming tube slidably mounted in said tube, a spring for forcing the tube partly out of the sleeve, an elongated slot in the sleeve, a projection on the tube extending through said slot, a finger pivoted on said projection and extending along the tube for clamping a strand of hair against the tube, the tube being provided with a slot, one end of the sleeve having an enlargement for holding a curl flatwisely against the head while the tube is forced out of the 40 curl, said enlargement being provided with a transverse guide for a hair pin, said hair pin guide being located in registration with the slot in the tube whereby a hair pin passed through the hair pin guide will also pass through the slot 45 and embrace the curl transversely of the axis of said curl while the curl is held by the enlargement against the head.
13. A hair curling device comprising, a sleeve, 50 a tubular curl-forming member telescopically mounted in the sleeve, a spring within the sleeve operative to force the curl-forming member partly out of the sleeve, an abutment on the sleeve for holding a formed curl against the head while the curl-forming member is forced out of 55 the curl by pressure of the end of said curl-forming member against the head, the abutment being provided with a plurality of transverse guide passages through which one or more hair pins may be passed to embrace the curl transversely 60 of the axis of said curl while the curl is held flatwisely against the head, the curl-forming member having a plurality of slots through which said pins pass, one of said slots being in registration with each of the guide passages. 65

MERVIN WIDEMAN.
